Primary Examiner — Catheri Oliver**CLAIM**

(57) The ornamental design for a combined tampon and pad pouch, as shown.

DESCRIPTION

FIG. 1 is a front and left side perspective view of the combined tampon and pad pouch showing my new design;

FIG. 2 is another front and left side perspective view with the pouch flap shown partially opened;

FIG. 3 is a front and right side perspective view with the pouch shown open. The environment is shown for illustrative purposes only and forms no part of the claimed design;

FIG. 4 is a rear view shown in a closed position;

FIG. 5 is a rear view shown open;

FIG. 6 is a second embodiment of the combined tampon and pad pouch showing my new design; the only difference between the embodiments being the slit opening that is shown on the front of embodiment one.

FIG. 7 is front and right side perspective view with the pouch shown open;

FIG. 8 is a side view shown open; and,

FIG. 9 is a side view shown closed.
